UNITED STATES PATENT OFFICE.

LOUIS R. PARSONS, OF TISKILWA, ILLINOIS.

RAIL-ANCHORING MEANS.

1,179,029.

Specification of Letters Patent.

Patented Apr. 11, 1916.

Application filed April 29, 1915. Serial No. 24,712.

To all whom it may concern:

Be it known that I, LOUIS R. PARSONS, a citizen of the United States, residing at Tiskilwa, in the county of Bureau and State 5 of Illinois, have invented certain new and useful Improvements in Rail-Anchoring Means; and I do declare the following to be a full, clear, and exact description of the invention, such as will enable others skilled in the art to which it appertains to make and use the same.

My invention relates broadly to improvements in railways and more particularly to means for anchoring the rails thereof to all 15 of the cross ties, thus preventing the latter from being shifted out of parallel relation to each other and likewise preventing the rails from running thereon.

The object of the invention is to provide 20 means of the class set forth which may be easily and inexpensively manufactured, which may be easily applied to use, and which will be highly efficient in operation.

With this general object in view, the invention resides in certain unique combinations of parts hereinafter fully described and claimed, one embodiment of the invention being shown in the accompanying drawing wherein like reference characters designate 25 corresponding parts throughout the several views and wherein:

Figure 1 is a side elevation of a portion of a railway showing the application of the anchoring means between the rails and the ties thereof; Fig. 2 is a vertical section through one end of one of the cross ties and the parts supported thereon; Fig. 3 is a top plan view of one of the anti-creeping plates; and Fig. 4 is a bottom plan view of a portion of one of the rails.

In this drawing which constitutes a part of the application, T designates a plurality of parallel cross ties to the opposite ends of each of which an anti-creeping plate 1 is im- 45 movably secured, preferably by four spikes 2 driven through the four corners of each plate, the heads of said spikes, however, being disposed in contact with the opposite edges of the base flange R of the rail R, whereby they not only serve to prevent shifting of the plates 1 upon the ties T but also as a means for preventing upward movement of the rail R resting on said plates.

As clearly shown in the several views of the drawing, each anti-creeping plate 1 is

provided on its under side with a plurality of V-shaped ribs 3 embedded in the ties T, while the upper side of said plate is equipped with a plurality of upstanding integral ribs 4 which are of considerably less length than the ribs 3, and which are preferably of rectangular formation. The ribs 4 are loosely received by similarly shaped sockets 5 which are punched in the base of the rail R when the same is rolled at the foundry, it being evident from Fig. 1 that the ribs 4 rather loosely engage the sockets 5, thus compensating for any expansion and contraction of the rails which may take place upon changes 70 in temperature. The ends of the ribs 4, however, abut the end walls of the sockets 5 rather closely in order that lateral thrust exerted upon the rail R will not be imparted directly to the spikes 2, but to the plates 1 75 through the instrumentality of said ribs. In addition to this disposition of plates for receiving lateral thrust, however, the outer longitudinal edges of the plates 1 are preferably provided with upstanding shoulders 80 6 which abut the outer longitudinal edge of the base of the rail.

It is to be understood that two plates 1 are secured to each of the several cross ties T, this disposition of plates being advantageous since running of the rails on the ties and shifting of the latter in respect to each other are both prevented. Furthermore, the rails are positively held against spreading by the construction in question.

From the foregoing description, when perused in connection with the accompanying drawing, all parts of the invention will be clearly understood by those skilled in the art to which the invention relates, and it will 90 be evident that the structure provided for accomplishing the desired ends will be highly advantageous although being simple and inexpensive.

I claim:

In combination, a plurality of cross ties, anti-creeping plates resting on the several ties and having longitudinally aligned shoulders on one edge, transverse integral ribs having upright ends being formed on the upper side of said plates at the intermediate portion thereof, a rail resting on the several plates and having one edge of its base disposed in contact with the aligned shoulders, said base having transverse sockets with upright end walls formed in its intermediate portion and opening through their lower

sides only and receiving the ribs therein, the upright ends of said ribs abutting the upright end walls of said sockets, spikes driven through the shoulders into the cross ties and 5 having their heads disposed in contact with the upper side of the base of the rail at one edge thereof, and additional spikes driven through the portion of the plates adjacent the opposite edge of said base, the heads of 10 said additional spikes being disposed in con-

tact with the upper side of this edge of the base.

In testimony whereof I have hereunto set my hand in presence of two subscribing witnesses.
